United States Patent

Des. 240,871
Patented Aug. 10, 1976

240,871

STOOL OR SIMILAR ARTICLE

Robert Herman, 3246 Baker St.,
San Francisco, Calif. 94123

Filed Sept. 3, 1974, Ser. No. 502,309

Term of patent 14 years

Int. Cl. D6—01

U.S. Cl. D6—32

FIG. 3

FIG. 1

FIG. 4

FIG. 2

FIG. 1 is an elevation view of one embodiment of a stool or similar article in accordance with this invention;

FIG. 2 is a perspective view on a reduced scale of the stool or similar article of FIG. 1;

FIG. 3 is an elevation view of a second embodiment of stool or similar article in accordance with this invention; and

FIG. 4 is a perspective view on a reduced scale of the stool or similar article of FIG. 3.

I claim:

The ornamental design for a stool or similar article, as shown.
